United States Patent Office

Des. 195,160
Patented Apr. 30, 1963

195,160

DISPLAY CABINET

James A. Waite, 11087 William St., and Frederick M.
Conroy, 11320 William St., both of Taylor, Mich.

Filed May 18, 1962, Ser. No. 70,206

Term of patent 14 years

(Cl. D80—11)

FIG. 1.

FIG. 2.

FIG. 3.

FIG. 4.

FIG. 1 is a front perspective view taken from one side of a display cabinet embodying our new design;

FIG. 2 is a rear perspective view taken from the side opposite that shown in FIG. 1 in an open position;

FIG. 3 is a top plan view of FIG. 1; and

FIG. 4 is a side elevational view of FIG. 1.

We claim:

The ornamental design for a display cabinet, as shown and described.
